G. C. THOMPSON

COVERED DISH OR ANALOGOUS ARTICLE

Filed May 6, 1926

FIG. 1.

FIG. 2.

Inventor

George C. Thompson,
By A. J. Patterson

Attorney

UNITED STATES PATENT OFFICE.

GEORGE CASSIUS THOMPSON, OF EAST LIVERPOOL, OHIO, ASSIGNOR TO THE C. C. THOMPSON POTTERY CO., OF EAST LIVERPOOL, OHIO.

DESIGN FOR A COVERED DISH OR ANALOGOUS ARTICLE.

Application filed May 6, 1926. Serial No. 17,589. Term of patent 7 years.

To all whom it may concern:

Be it known that I, GEORGE C. THOMPSON, a citizen of the United States, residing at East Liverpool, in the county of Columbiana and State of Ohio, have invented a new, original, and ornamental Design for a Covered Dish or Analogous Article, of which the following is a specification, reference being had therein to the accompanying drawings.

The predominant feature of the design is the angular effect given to the entire dish. This effect in the dish provides a series of flat side wall faces arranged at angles to

one another. The same effect is carried out in the dish cover, both at its lower edge and in its raised central top portion.

In the drawings:

Figure 1 is a view in side elevation of the article, showing my new design.

Figure 2 is a top plan view thereof.

I claim:

The ornamental design for a covered dish or analogous article, as shown and described.

In testimony whereof, I hereunto affix my signature.

GEORGE CASSIUS THOMPSON.
